UNITED STATES PATENT OFFICE.

ERNEST R. LUNDQUIST, OF LINCOLN, NEBRASKA.

EXTENSION STEP.

Application filed September 24, 1926. Serial No. 137,562.

This invention relates to improvements in steps especially designed for vehicles and has for an object the provision of auxiliary steps adapted to be attached to the main steps of a car or other vehicle, so as to provide an extension for the main steps and safer and more convenient entrance and exit to and from a car.

Another object of the invention is the provision of auxiliary steps for the above purpose, which may be readily attached to the main steps, and which in addition, are simple and durable in construction; are provided with novel means to hold them against accidental movement, and may be readily moved to an active or inactive position.

With the above and other objects in view, the invention further includes the following novel features and details of construction, to be hereinafter more fully described, illustrated in the accompanying drawings and pointed out in the appended claims.

In the drawings:—

Figure 1 is an elevation showing a fragmentary portion of a car with the invention applied, the auxiliary steps being shown in extended position.

Figure 2 is a similar view with the auxiliary steps folded.

Figure 3 is a front view with the parts in the position shown in Figure 1.

Figure 4 is a fragmentary section on the line 4—4 of Figure 2.

Figure 5 is a detail perspective view of one of the risers of the auxiliary steps.

Figure 6 is a similar view of one of the treads.

Figure 7 is an enlarged fragmentary section on the line 7—7 of Figure 3.

Referring to the drawings in detail where in like characters of reference denote corresponding parts, the reference character C indicates a portion of a car, from the platform P of which extend the usual permanent or main steps S. These steps are of the usual or any preferred construction and include side walls 10, while the auxiliary steps are secured to and extend from the lowermost of the main steps.

The auxiliary steps comprise treads 11 and risers 12, the latter having their opposite edges hingedly secured to the front and rear edges of the treads as shown at 13 and 14. For this purpose, the treads and risers are provided with spaced eyes 15 for the passage of pivot pins or pivot rods.

The front edges of the treads 11 are provided between the eyes 15 with downwardly extending flanges 16, which, in the case of one of the treads, hinges over the adjacent edge of one of the risers and acts to limit outward pivotal movement of the latter. Extending along the inner edge of the treads 11 between the eyes 15 is an upwardly extending flange 17 which engages the adjacent edge of the adjacent riser and acts to limit downward pivotal movement of the treads.

The topmost riser 12 is hingedly secured as shown at 18 to the bottom steps 10, so that the auxiliary steps may be folded upward and inward beneath the steps 10 as shown in Figure 2 of the drawings, or may be extended downward and outward as shown in Figures 1 and 3.

Secured to the lowermost tread at opposite ends thereof are bars 19. These bars incline upwardly and inwardly and have their upper ends received in guide housings 20, which are provided with slots 21. The bars 19 carry outwardly extending pins 22 which have pivotally mounted thereon links 23. These links are in turn pivotally mounted to arms 24 whose inner ends are rigid upon the outer ends of a rock shaft 25. This shaft is mounted in bearing brackets 26 which are secured to and depend from the main steps 10, so that by rocking the shaft 25, the bars 19 may be slid upwardly so as to fold the steps as shown in Figure 2 of the drawings. Secured to the rock shaft 25 is an operating handle 26', which, when in the raised position shown in Figure 2, is adapted to be received within a yoke 27 which is pivotally mounted upon the main steps 10 as shown at 28. When in their lowered or extended position, the auxiliary steps carry lugs 29 which engage the edges of the bars 19 and act to resist outward swinging movement of the steps when the latter are in their lowered position.

It will be apparent from the foregoing description and accompanying drawings that the invention provides a simple, strong and durable set of auxiliary steps which may be attached to main steps for the purpose of providing an extension for the latter, whereby passengers passing into and out of cars or similar vehicles may do so with comfort and convenience and without the risk attendant upon the use of the stool usually employed for that purpose. Frequently, a stool will tilt, so that the passenger is in

danger of injury or inconvenience from this cause.

The invention is susceptible of various changes in its form, proportions and minor details of construction and the right is herein reserved to make such changes as properly fall within the scope of the appended claims.

Having described the invention what is claimed is:—

- 10 1. The combination with main steps, of
auxiliary steps hingedly secured to the main
steps, means hingedly connecting the risers
and threads of the auxiliary steps to permit
the said auxiliary steps to fold upward
15 beneath the main steps, and an inclined bar
extending upwardly and inwardly from each
side of the lowermost auxiliary step, means
at opposite sides of the main steps to slid-
20 ingly receive the bars, a rock shaft extend-
ing transversely across and supported be-
neath the main steps, an arm secured to one
25 end of the rock shaft, a link connecting the
arm and one of the inclined bars, whereby
rocking movement of the shaft will move the
bars longitudinally to fold or extend the
auxiliary steps, an operating lever secured
30 at one end of the shaft and means to hold the
lever against operation.

2. The combination with main steps, of
auxiliary steps hingedly secured to the main
steps, means hingedly connecting the risers
35 and threads of the auxiliary steps to permit
the said auxiliary steps to fold upward be-
neath the main steps, and an inclined bar ex-
tending upwardly and inwardly from each
40 side of the lowermost auxiliary step, means
at opposite sides of the main steps to slid-
ingly receive the bars, a rock shaft extend-
ing transversely across and supported be-
neath the main steps, an arm secured to one
45 end of the rock shaft, a link connecting the
arm and one of the inclined bars, whereby
rocking movement of the shaft will move the
bars longitudinally to fold or extend the
auxiliary steps, an operating lever secured at
50 one end of the shaft and a pivotally mounted
lever engaging yoke carried by the main
steps.

3. The combination with main steps, of
opposite sides of the auxiliary steps and en-
gaging the bars to resist outward swinging
movement of said auxiliary steps, a rock
55 shaft extending transversely across and sup-
ported beneath the main steps, an arm se-
cured to one end of the rock shaft, a link
connecting the arm and one of the inclined
bars, whereby rocking movement of the shaft
60 will move the bars longitudinally to fold or
extend the auxiliary steps, an operating lever
secured to one end of the shaft and means
to hold the lever against operation.

4. The combination with main steps, of
auxiliary steps hingedly secured to the main
steps, means hingedly connecting the risers
and threads of the auxiliary steps to permit
said auxiliary steps to fold upward beneath
65 the main steps, means carried at opposite
edges of the treads and engaging the risers
of the auxiliary steps to limit independent
pivot movement of said treads and risers
in one direction, and means connecting the
70 main and auxiliary steps to move the latter
to an active or inactive position.

5. The combination with main steps, of
auxiliary steps hingedly secured to the main
steps, means hingedly connecting the risers
and threads of the auxiliary steps, to permit
the said auxiliary steps to fold upward be-
75 beneath the main steps, flanges extending along
opposite edges of the threads and engaging
the risers of the auxiliary steps to limit
independent pivotal movement of said treads
and risers in one direction and means con-
80 nnecting the main and auxiliary steps to
move the latter to an active or inactive posi-
tion.

In testimony whereof I affix my signature.

95

ERNEST R. LUNDQUIST.

auxiliary steps hingedly secured to the main steps, means hingedly connecting the risers and treads of the auxiliary steps to permit the said auxiliary steps to fold upward beneath the main steps, an inclined bar extending upwardly and inwardly from each side of the lowermost auxiliary step, means at opposite sides of the main steps to slidably receive the bars, lugs extending from opposite sides of the auxiliary steps and engaging the bars to resist outward swinging movement of said auxiliary steps, a rock shaft extending transversely across and supported beneath the main steps, an arm secured to one end of the rock shaft, a link connecting the arm and one of the inclined bars, whereby rocking movement of the shaft will move the bars longitudinally to fold or extend the auxiliary steps, an operating lever secured to one end of the shaft and means to hold the lever against operation.

4. The combination with main steps, of auxiliary steps hingedly secured to the main steps, means hingedly connecting the risers and treads of the auxiliary steps to permit said auxiliary steps to fold upward beneath the main steps, means carried at opposite edges of the treads and engaging the risers of the auxiliary steps to limit independent pivotal movement of said treads and risers in one direction, and means connecting the main and auxiliary steps to move the latter to an active or inactive position. 75 80

5. The combination with main steps, of auxiliary steps hingedly secured to the main steps, means hingedly connecting the risers and threads of the auxiliary steps, to permit the said auxiliary steps to fold upward beneath the main steps, flanges extending along opposite edges of the threads and engaging the risers of the auxiliary steps to limit independent pivotal movement of said treads and risers in one direction and means connecting the main and auxiliary steps to move the latter to an active or inactive position. 85 90 95

In testimony whereof I affix my signature.
